UNITED STATES PATENT OFFICE

JOHAN WERNER JOHANSSON, OF BANKERYD, SWEDEN

MATCH PACKAGE

Application filed October 14, 1930, Serial No. 488,845, and in Sweden September 2, 1930.

This invention relates to match packages having a row of matches connected with a common base strip, from which the matches are torn off, when they are to be used. In 5 packages of this type it was already proposed to fold the matches down on the base strip, at some distance from their base. The matches may thus be grasped at the fold, when they are to be torn off from the base 10 strip. The match strip thus folded may be provided with a special cover which is attached to the undivided base strip of the matches and is folded around the matches in a manner known in itself. The friction surface 15 may be placed on the outer surface of the cover and, by preference, just at the same level as the undivided base strip. In such packages the matches are easily brought into disorder, after a few matches have been taken from the packages, because the matches then 20 will not guide each other any more. This is particularly so, when the wrapper round the match heads is not secured to the base strip by means of staples or the like. Consequently 25 the matches are easily bent in the lateral direction at their fold to lie obliquely in the package having their heads in a dangerous proximity to the striking surfaces. Thus, the matches may be ignited unintentionally 30 and, moreover, it is rather difficult to draw them out of the package. The chief object of this invention is to overcome such inconveniences and to effect that the remaining matches are always kept in their correct position in the package, even if the cover is 35 loosely wrapped round the heads of the matches.

A further object of this invention is to simplify the package proper still more by lengthening the base strip so much that it may be folded around the heads of the matches and thus serve as a cover for the matches. Preferably, the base strip is provided at its inner side with friction surfaces on one side or on 45 both sides of the row of matches, so that the matches are ignited when they are drawn out between the opposite portions of the base strip, said portions being pressed against the row of matches either by hand at each occasion of use or by particular means acting 50

permanently, for instance, by connecting the folded portion of the base strip, at those edges of said portion, which are parallel to the matches, with the remaining portion of the base strip. 55

The match package which is made of paper, cardboard, or other suitable material, is thus extremely simple to manufacture and is very compact. The package is consequently very fit for being placed in cigarette boxes, 60 for instance, at the under side of the inner box or in a pocket on the outer box. 65

One embodiment of the invention is illustrated in the annexed drawing.

Fig. 1 shows a cutting for a package before the folding. 66

Fig. 2 is an end view and

Fig. 3 plan of the package as folded. 68

Referring now to the drawing 1 indicates a row of matches formed by making incisions 70 in a strip of paper or cardboard from one side in such manner that the matches are integral with and connected by a common uncut base strip 2. In order to facilitate the separation of the matches from the base strip perforations 3 are made at the base of the matches to weaken the matches there. In the finished package the matches are, at some distance from their base, folded towards the base strip 2 along a folding line 4 in such manner that 75 the free ends carrying the heads 5 of the matches will lie close by the centre line of the base strip 2. The folded portion or flap of the matches may be fixed to the non-folded portion by an adhesive applied in the fold in 80 order to prevent the folded portion from separating from the non-folded portion due to the resiliency of the material at the folding line. The surplus portion 7 of the strip 2 is folded along a folding line 6 to cover the matches 85 thus folded and consequently the base strip serves as a cover for the matches. The folded, double pasted portions 8 of the matches project, however, from the cover and may easily be seized, when the matches are to be torn off 90 from the base strip. The latter is at its inner sides provided with friction surfaces 9 and 10 on both sides of the row of matches, viz. below the base of the matches and also at that portion of the folded part 7 of the base strip 95 100

which is just opposite to the first-mentioned friction surface after the folding. When the sides of the cover are pressed together and a match torn off from the base strip and withdrawn, the head 5 of this match will pass between the friction surfaces thus pressed together and consequently be ignited. In order to secure that the outermost matches of the row are brought into contact with the friction surfaces, when withdrawn, and to prevent them from passing outside said surfaces, the total width of the matches is made less than the width of the cover, as seen in Figs. 1 and 3. The edges of the base strip which are parallel to the matches are thus projecting outside the row of matches and the adjacent one of these projecting edge may be united together by means of wire staples 11, an adhesive or the like. This forces the outermost matches of the row to pass between the friction surfaces, which are thus permanently kept pressed against the row of matches with the pressure necessary for igniting the heads of the matches. Even if some matches have been torn off from the package the remaining matches will not be brought in disorder because of the adhesive between the surfaces of the double, folded ends 8, which rest against each other.

20 The staples 11 may be dispensed with, because the matches will remain in their places and not spring out from the base strip, the double portions of their ends 8 being pasted together.

25 The very process of manufacture is also facilitated by the fact that the two folded portions of the matches are pasted together, because the matches cannot get entangled and the strip of folded matches becomes more easy 40 to manage, the matches being prevented from springing out from the strip.

When the match package is to be applied to a cigarette box consisting of an outer box and an inner box slidable therein the match package is, preferably, attached to the under side of the inner box by means of a wire staple or an adhesive in such manner that the folded, double pasted ends 8 of the matches may be seized when the inner box has 50 been partially pushed out. The match package may, however, also be placed in a pocket on the outer box. If the width of such pocket is made equal to the width of the match package, any particular measures need not be 55 taken on the match package to guide the outermost matches, when they are drawn out.

What I claim is:

1. In a match package, a row of matches formed integral with a common base strip, the upper head-carrying portions of said matches being at some distance from said base strip folded down on said base strip, and means for attaching together the portions of said matches folded on each other.

2. In a match package, a row of matches

formed integral with a common base strip, said base strip being slightly broader than the total width of said row of matches, a fold in said base strip on a line at right angles to said matches, heads on the ends of said matches remote from said base strip, means for weakening said matches at their bases, the upper head-carrying portions of said matches being at a distance from said base strip folded down on said base strip into the 70 fold therein, the portions of said matches folded down being secured to the unfolded portions thereof by an adhesive, one or more friction surfaces at the inner side of said folded base strip on one side at least of said 75 row of matches at a greater distance than said heads from the fold in said base strip, and means for joining together the edges of said folded base strip, which are parallel to said matches.

3. In a match package, a row of matches formed integral with a common base strip, said base strip being folded on a line at right angles to the longitudinal direction of the matches, incisions to weaken said matches at 90 their bases, the upper head-carrying portions of said matches being folded down at a distance from said base strip to have their heads in the fold of said strip, means for attaching together the portions of each match folded down on each other, and at least one friction surface at the inner side of said folded base strip on one side at least of said row of matches at a greater distance than said heads from the fold in said base strip. 100

In testimony whereof I have signed my name.

JOHAN WERNER JOHANSSON.
